TANK-FILLING VALVE

William T. Roberts, Scranton, Pa., assignor of
one-half to Stephanie Wolongiewicz, Scranton,
Pa.

Application October 15, 1946, Serial No. 703,307

4 Claims. (Cl. 137—104)

1

The invention relates to a float-actuated tank-filling valve designed primarily for use in a closet flush tank, although not restricted to this use.

The principal object of the invention is to provide a novel construction which can be locked (by an actual lock or by a seal) against such adjustment as to obtain an abnormally high water level in the flush tank, thus preventing needless waste of water, the invention being thus particularly advantageous in apartment houses and office buildings, although of advantage also in numerous other buildings.

A further object is to provide a novel construction which permits an authorized person to vertically adjust the float to any required extent without the necessity of bending a float-carrying arm, as now customary.

A still further object is to provide a construction which will be simple and inexpensive, may be easily installed as a substitute for the usual float and arm of a common ball cock, and will be effective and durable.

Fig. 1 of the accompanying drawings is a vertical longitudinal sectional view through a portion of a flush tank, showing in elevation a ball cock improved in accordance with the present invention, the locking casing being shown in vertical section.

Fig. 2 is a rear elevation, partly broken away, of the parts shown in Fig. 1, except that the locking casing is removed.

Fig. 1a is an edge view of the locking casing with its hinged top swung upwardly.

Fig. 3 is a top plan view of the parts shown in Fig. 1, except that the cover of the flush tank is removed and the locking casing is removed.

Fig. 4 is a fragmentary disassembled perspective view showing the parts which are secured to the operating lever of the tank-filling valve or ball cock, and one end of the float.

Fig. 5 is a horizontal sectional view on line 5—5 of Fig. 4.

Fig. 6 is a side elevation showing an adapter which is used if the tank-filling valve or ball cock be of the type having an unusually short actuating lever.

Preferences have been shown in the drawings and will be rather specifically described, with the understanding, however, that within the scope of the invention as claimed, variations may be made.

In the drawings above briefly described, a flush tank 1 is shown containing a well known tank-filling valve or ball cock 8, an overflow pipe 9, a refill tube 10, and a flush valve 11 with which suitable actuating means 12 is connected in the

2

usual way. The valve 8 includes the usual vertically swingable actuating lever 13 which is ordinarily connected with a float-carrying arm, but when the improvements of the present application are installed, said arm and its float are dispensed with. If the lever 13 be relatively long as seen in Figs. 1 to 3, all parts of the present improvement will clear the valve 8 and no adapter is necessary on the free end of said lever 13. However, if the lever be unusually short, it is provided with an extension or adapter 14 (Fig. 6). As ball cocks are now customarily made, the free end of the actuating lever is formed with a threaded socket 15 extending longitudinally of the lever and opening through its free extremity. The adapter or lever extension 14 is provided with an integral stud 16 to be tightly threaded into the socket 15 if the lever 13 be short, and the outer end of said adapter or extension is formed with a socket 15a corresponding to the socket 15. Thus, whether the lever 13 be originally short or comparatively long, it will include an accessible socket (15 or 15a) opening through its free terminal. I utilize this socket to receive the threaded end of a clamping screw 17 which secures my improvements to the lever 13, said screw having a head 18 at its outer end which is preferably so constructed that a nail or the like may be readily engaged with it to tighten said screw.

Attached to the valve-actuating lever 13 by means of the screw 17, is a vertically elongated body 19 having a vertical slot 20 through which said screw extends, said body being tightly clamped against the free terminal 21 of said lever, by means of said screw. The body 19 is provided with an integral rigid arm 22 which extends away from the tank-filling valve 8, said arm 22 preferably having a lateral inner end 23 and a horizontally directed lateral outer end 24, said outer end 24 having a longitudinal slot 25. Contacting with the outer side of this lateral arm end 24, is one end wall 26 of a horizontally elongated float 27, said float being rather narrow horizontally and preferably having a reduced neck portion 28 to insure that it shall clear the overflow pipe 9. The float end 26 rigidly carries a stud 29 and is provided with a flat-sided boss 30 at the inner end of said stud. The stud extends through the slot 25 and the boss 30 is non-rotatably received in this slot, and a nut 31 and washer 32 are applied to said stud, whereby the float 27 is rigidly attached to the lateral end 24 of the arm 22 and may be horizontally adjusted as required with respect to said arm.

An L-shaped slide 33 has one of its arms 34

clamped against one edge of the body 19, by means of the screw head 18, said arm 34 having an opening 35 through which the screw 17 extends. The other arm 36 of the slide 33 extends across one vertical side of the body 19 and projects beyond said body into overlapping relation with the free end portion of the lever 13. A set-screw 37 is threaded through this arm 36 and is pointed to bite into the lever 13, thus holding the body 19 against turning about the screw 17 as a pivot. To hold the arm 36 against outward springing from the body 19, when the set-screw 37 is tightened, I provide said arm and body with inter-hooked flanges 38 and 39. These inter-hooked flanges also coact with the end 34 of the slide 33, in establishing a slideable connection between said slide and the body 19. This slideable connection permits vertical adjustment of the body 19 with respect to the lever 13, when the clamping screw 17 is released and it is, therefore, possible to vertically adjust the member 19 to dispose the float 27 at the proper elevation to insure a water level of the desired height. After this adjustment is obtained and the screw 17 again tightened, access to said screw for further adjustment, by unauthorized persons, is prohibited due to the provision of the locking means or the like shown in Figs. 1 and 1a but omitted from the other views, which means is described below.

A casing 40 is provided to enclose the vertically elongated body 19 and its adjusting means, said casing including one vertical side wall 41 between the screw head 18 and the float end 26, and two opposed side walls 42 and 43 disposed at opposite sides of the body 19, the side wall 43 being formed with a notch 44 which receives the lateral inner end 23 of the arm 22. The casing 40 also includes a bottom 45 extending under the body 19, and a hinged upwardly swingable top 46 to extend over the upper end of said body 19. This body is provided with an upwardly projecting hasp 47 receivable in a slot 48 in the top 46 and adapted for engagement with a padlock 49, (or with a seal) (not shown). The bottom 45 is provided at its free edge with an upwardly projecting flange 50 which prevents movement of the lower end of the casing out of enclosing relation with the body 19, until said casing can be lowered. As long as the top 46 is held in place by the lock or seal, however, the casing cannot lower and consequently, it will be held in the operative position shown in Fig. 1, barring access to the screw head 18 and hence, prohibiting vertical adjustment of the float 27 with respect to the lever 13 by an unauthorized person and, therefore, preventing waste of water which might otherwise occur. When the locking means (padlock or seal) is released and the cover 46 swung upwardly as seen in Fig. 1a, the casing 40 may be lowered after it is swung laterally to disengage the notch 44 from the end 23 of the arm 22, thus permitting detachment of the casing when adjustment is to be made by a person authorized to make said adjustment.

It will be noted that the invention may be manufactured at low cost and put on the market either in new closet tanks or sold independently

to the public as a complete replacement unit for tanks that are already in use, thus making it about 98% universal.

The old practice of bending the float rod to adjust the amount of water in the tank is not practical. By so doing, the float often drops down too far and holds the rubber tank ball open so that it cannot operate as intended to shut off and hold water in the tank, causing water to waste in great quantities.

From the foregoing, taken in connection with the accompanying drawings, it will be seen that novel and advantageous provision has been made for attaining the desired ends, and while preferences have been disclosed, attention is again invited to the possibility of making variations within the scope of the invention as claimed.

I claim:

1. An adjustable connection for use between 20 a valve-actuating lever and a float carried thereby, said adjustable connection comprising a vertically elongated body having one side to abut the extremity of a lever for vertical adjustment with respect thereto, a headed clamping screw 25 extending through said body for engagement with a threaded socket at the extremity of a lever for clamping said body in adjusted position, and a rigid float-carrying arm on said body and extending away from the other side of said body to form a lever extension.

2. A structure as specified in claim 1 in which 30 said body has a vertical slot through which said clamping screw extends.

3. A structure as specified in claim 1 in which 35 said rigid arm is U-shaped and has one end integral with and projecting laterally from said body, and its other end slotted to receive a fastening for the attachment of a float.

4. An adjustable connection for use between 40 a valve-actuating lever and a float carried thereby, said adjustable connection comprising a vertically disposed, rectangular body having a vertical slot and a flange along one of its sides, said flanged side being adapted to slidably abut the 45 extremity of a lever to permit vertical adjustment of said body, an L-shaped slide positioned across said flanged side of the body and having a flange to engage said flange on the body, the other arm of said L-shaped slide having an 50 opening in alignment with said vertical slot, a headed clamping screw extending through said aligned opening and slot for engagement with a threaded socket in a lever for clamping said body in adjusted position, a set screw in said slide for engagement with a lever to prevent said body from turning on said clamping screw, and a rigid float-carrying arm on said body.
